(57) **CLAIM**

The ornamental design for a mobile phone, as shown and described.

DESCRIPTION

FIG. 1 is a perspective view of a mobile phone showing our new design; and,

FIG. 2 is a front elevational view thereof.

The broken lines immediately adjacent the unclaimed surfaces represent boundaries of the claimed design. All other broken lines depict unclaimed environment. The broken lines and regions bounded by broken lines form no part of the claimed design.
